UNITED STATES PATENT OFFICE.

ELIZABETH F. WASHBURN, OF WARE, MASSACHUSETTS.

DESIGN FOR A BOOK END OR SIMILAR ARTICLE.

Application filed October 14, 1925. Serial No. 15,119. Term of patent 3½ years.

To all whom it may concern:

Be it known that I, ELIZABETH F. WASHBURN, a citizen of the United States, residing at Ware, in the county of Hampshire and State of Massachusetts, have invented a new, original, and ornamental Design for a Book End or Similar Article, of which the following is a specification, reference being had to the accompanying drawing, forming part thereof.

Fig. 1 is an elevational view of a book end or similar article showing my new design.

Fig. 2 is an edge elevational view thereof.

I claim:

The ornamental design for a book end or similar article, as shown.

ELIZABETH F. WASHBURN.
